SWITCH HOUSING

Robert M. Wolaver, Maumee, Ohio, assignor to Manning,
Maxwell & Moore, Incorporated, Muskegon, Mich., a
corporation of New Jersey

Filed Mar. 24, 1960, Ser. No. 59,857

Term of patent 14 years

(Cl. D26—13)

fig.3.

fig.4.

Figure 1 is a perspective of a switch housing embodying the new design;

Fig. 2 is a front elevation of the unit shown in Fig. 1;

Fig. 3 is a side elevation of the unit shown in Fig. 1; and

Fig. 4 is a rear elevation of the unit shown in Fig. 1.

The left and right sides of the switch housing shown in the drawings are similar.

The broken line showing of a connecting cable and the legible indicia are only for illustrative purposes. The dominant features of my new design are shown in solid lines in the drawings.

I claim:

The ornamental design for a switch housing, substantially as shown and described.
